UNITED STATES PATENT OFFICE.

JAMES H. HOLLAND, OF AURORA, MISSOURI.

IMPROVEMENT IN COMBINED LAND-ROLLERS AND SEEDING-MACHINES.

Specification forming part of Letters Patent No. 158,712, dated January 12, 1875; application filed July 3, 1874.

To all whom it may concern:

Be it known that I, JAMES HIRAM HOLLAND, of Aurora, in the county of Lawrence and State of Missouri, have invented a new and useful Improvement in Combined Seed-Drill, Corn-Planter, Land-Roller, and Cultivator, of which the following is a specification:

Figure 1 is a top view of my improved machine, part being broken away to show the construction. Fig. 2 is a side view of the same, partly in section through the line $x x x$, Fig. 1.

Similar letters of reference indicate corresponding parts.

The invention will first be fully described, and then pointed out in the claim.

A represents the frame of the machine, to the lower side of the rear part of the side bars

of which are attached brackets B, in which revolve the journals of the shaft C, upon which the parts of the roller D are placed. The roller D is made in two parts, and to its outer ends are detachably bolted the wheels E, one or both of which are rigidly connected with the shaft C, so as to carry said shaft with them in their revolution.

Having thus described my invention, I claim as new and desire to secure by Letters Patent—

The combination of the detachable wheels E and roller D with the shaft C and frame A, in the manner set forth.

JAMES HIRAM HOLLAND.
